Klaus P. Stoffel(57) **CLAIM**

The ornamental design of a battery, as shown and described.

DESCRIPTION

1. Battery

1.1 is a bottom view;

1.2 is a side view;

1.3 is a rear view;

1.4 is a front view;

1.5 is a top view;

1.6 is a side view; and

1.7 is a perspective view.

The portions of the battery shown with broken lines form no part of the claimed design.
